BLISTER PACKAGE

Paul E. Moberly, Schoolcraft Township, Kalamazoo County, and Harold E. Rudlaff, Kalamazoo, Mich., assignors to The Upjohn Company, Kalamazoo, Mich.

Filed Jan. 22, 1973, Ser. No. 325,863

Term of patent 14 years

Int. Cl. D9—03

U.S. Cl. D9—192

FIG. 1

FIG. 5

FIG. 3

FIG. 4

FIG. 6

FIG. 2

FIG. 7

FIG. 1 is a front elevational view of a blister package embodying our new design;

FIG. 2 is a rear elevational view thereof;

FIG. 3 is a top view thereof;

FIG. 4 is a bottom view thereof;

FIG. 5 is a side elevational view as taken from the right side of FIG. 1;

FIG. 6 is a side elevational view as taken from the left side of FIG. 1; and

FIG. 7 is a right side elevation of the handle, the bottle being shown in broken lines for illustrative purposes only.

We claim:

The ornamental design for a blister package, as shown and described.
